(57) CLAIM

The ornamental design for a mobile audio headset, as shown and described.

DESCRIPTION

A portion of the disclosure of this design patent document contains material to which a claim of copyright protection is made. The copyright owner has no objection to the facsimile reproduction of the patent document or the patent disclosure as it appears in the U.S. Patent and Trademark office file or records, but reserves all other copyright rights.

FIG. 1 is a perspective view of a mobile audio headset, in accordance with the present invention;

FIG. 2 is a side view thereof;

FIG. 3 is a back view thereof;

FIG. 4 is a corresponding side view thereof;

FIG. 5 is a top view thereof;

FIG. 6 is an underside view thereof; and,

FIG. 7 is a front view thereof.
